MULTICOPY ATTACHMENT FOR TYPE-WRITING MACHINES

Beulah Louise Henry, New York, N. Y.

Application November 8, 1949, Serial No. 126,121

7 Claims. (Cl. 197—153)

1

This invention relates to attachments for typewriting machines for simultaneously producing a plurality of ink copies.

The invention has in view a multicopy attachment providing an ink impregnated supplemental ribbon which is adapted to be interposed between sheets of paper arranged in a typewriting machine with the supplemental ribbon disposed in parallel relation with the typewriter ribbon for producing ink impressions on the sheets corresponding to the type impression on the original copy.

Another object of the invention is to provide a multicopy attachment of said character which is constructed and arranged for swinging movement to dispose the supplemental ribbon in operative position in parallel relation with the typewriter ribbon or in an out-of-the-way inoperative position at one side of the typewriter to permit of the convenient insertion of the sheets of paper in the typewriter.

Another object of the invention is to provide means for the supplemental ribbon which normally spaces the ribbon from the sheets of paper so as to prevent smudging contact of the ribbon therewith and which engages the paper only when the type strikes the typewriter ribbon.

Another object of the invention is to provide means for spreading the ribbon guide means apart with the movement of the attachment into the out-of-the-way inoperative position and for moving the said guide means into close relation with the swinging movement of the attachment into operative position.

Another object of the invention is to provide a multicopy attachment of said character in which the supplemental ribbon is moved longitudinally within the guide means with the movement of the typewriter carriage from left to right for presenting different portions of the ribbon in position for producing the type impression on the paper.

Another object of the invention is to provide means for automatically reversing the direction of movement of the supplemental ribbon in the guide means for winding one end thereof on a spool and unwinding the opposite end thereof from another spool and vice versa.

Another object of the invention is to provide ribbon guide means in the form of channels having longitudinally extending rectangular openings in the opposite faces thereof for engagement of the supplemental ribbon against the sheets of paper for receiving the type impression thereon.

2

Still another object of the invention is to provide an attachment of said character which can be conveniently applied to and removed from any standard typewriting machine.

With the foregoing and other objects in view, reference is now made to the following specification and accompanying drawings in which the preferred embodiment of the invention is illustrated.

10 In the drawings:

Fig. 1 is a top plan view of a typewriting machine equipped with a multicopy attachment constructed in accordance with the invention.

Fig. 2 is an enlarged fragmentary view of the upper portion of the typewriting machine with the attachment shown in operative position thereon in full lines and in an out-of-the-way inoperative position in broken lines.

Fig. 3 is an enlarged fragmentary rear view 15 of the attachment and carriage of the typewriting machine.

Fig. 4 is an enlarged transverse sectional view taken approximately on line 4—4 of Fig. 1.

Fig. 5 is an enlarged fragmentary sectional 20 view taken approximately on line 5—5 of Fig. 1.

Fig. 6 is an enlarged fragmentary sectional view taken approximately on line 6—6 of Fig. 4.

Fig. 7 is an enlarged fragmentary sectional view taken approximately on line 7—7 of Fig. 6.

Fig. 8 is an enlarged fragmentary sectional 25 view taken approximately on line 8—8 of Fig. 2.

Fig. 9 is an enlarged view taken approximately on line 9—9 of Fig. 2 showing the supplemental ribbon in section.

Fig. 10 is a similar view with the guide means 30 spread apart.

Fig. 11 is an enlarged fragmentary sectional view taken approximately on line 11—11 of Fig. 9.

Fig. 12 is an enlarged sectional view taken approximately on line 12—12 of Fig. 2.

Fig. 13 is an enlarged fragmentary sectional 35 view taken approximately on line 13—13 of Fig. 1.

Fig. 14 is an enlarged sectional view taken approximately on line 14—14 of Fig. 13.

Fig. 15 is a fragmentary perspective view of 40 the supplemental ribbon guide means showing fragmentary portions of the sheets of paper in position with reference thereto.

Fig. 16 is an end view of the attachment.

Fig. 17 is a sectional view taken approximately 45 on line 17—17 of Fig. 16.

Fig. 18 is a modified form of the guide means for the auxiliary ribbon.

Fig. 19 is a longitudinal sectional view taken 50 approximately on line 19—19 of Fig. 18.

Fig. 20 is a sectional view through one of the spools taken approximately on line 20—20 of Fig. 4.

Fig. 21 is an edge view of the torque limiting reversing clutch and associated discs shown in section in Fig. 7.

Fig. 22 is a fragmentary sectional view taken approximately on line 22—22 of Fig. 3.

Referring to the drawings by characters of reference, the attachment indicated generally by the reference character A is affixed to a standard typewriter B which includes the usual frame 10 and keys 11 operatively connected with the type bars 12 for striking movement of the keys against the ink ribbon 13. The ribbon 13 is trained through the ribbon carrier 14 and is disposed in front of the platen or roller 15 mounted for rotation on the reciprocatory carriage 16.

The attachment A consists of a head 18 having a rectangular frame 19 which includes a plurality of guide sheaths, two such sheaths 20 and 21 being shown in the present embodiment, in which two leads or courses 22 and 23 of a supplemental ribbon 24 are arranged respectively for longitudinal sliding movement. The sheaths 20 and 21 are formed with longitudinally extending slots 26 and 27 in the opposite walls thereof which slots are of a width to receive the type impression as the type strikes the typewriter ribbon. The arrangement is such that a plurality of sheets of paper trained around the platen or roller will extend upwardly across the sheaths with one sheet disposed in front of each of the sheaths and one sheet at the rear of each of the sheaths so as to produce two ink copies on the forward faces of two of the sheets and two ink copies on the rear faces of two of the sheets in addition to the original copy or type impression produced by the typewriter ribbon.

The head 18 together with the rectangular frame 19 is mounted for swinging movement from an inoperative out-of-the-way upwardly directed position as shown in broken lines in Fig. 2 of the drawings to an operative position in which the rectangular frame 19 is disposed longitudinally of the machine and the sheaths 20 and 21 are arranged between the type guide 25 and the platen or roller 15 as illustrated in full line in Fig. 2 of the drawings. For such purpose the head 18 is pivoted on a pivot pin 29 journaled in pintles 30 carried by a plate 31 which is secured to the right hand end of the carriage frame 32 by screws 33 or equivalent fastening means.

Affixed to the head 18 is a forwardly disposed housing 34 in which two gears 35 and 36 are mounted for rotation on stub shafts 37 and 38 secured at their inner ends in openings in the rear wall 39 of the housing with the hubs 40 and 41 respectively of the gears protruding through openings in a partition wall 42 and forming spools on which the ends of the supplemental ribbon 24 are wound. From the hub or spool 40 the lead or course 22 of the supplemental ribbon is trained through a slot 47 in the side wall of the housing 34 and thence extends vertically downward and through a slot 48 in the extension 49 of the housing 34. The slot 48 is disposed at an angle of 45° to the horizontal to turn the lead or course 22 horizontally into the open end 44 of the sheath 20 secured to the extension 49. From the hub or spool 41, the lead or course 23 of the supplemental ribbon 24 is trained through a slot 50 in a spring latch 52 pivoted to the housing on a pivot pin 53 and to which spring latch the right hand end of the sheath 21 is affixed.

From the slot 50 the lead or course 23 extends through a slot 54 in said spring latch which is located at an angle of 45° to the horizontal so as to direct the lead or course horizontally into the open end 45 of the sheath 21. The said lead or course extends longitudinally through the sheath 21 and is trained about the outer periphery of a vertically disposed post 56 where it continues with the lead or course 22.

In order to drive the gears 35 and 36 for winding the supplemental ribbon on the spools, a torque limiting reversing clutch is provided which includes spaced discs 57 and 58 having pinions 59 and 60 disposed in meshing engagement with said gears respectively and which discs are mounted for rotation on aligned shafts 61 and 62 formed integrally with oppositely disposed annular sections 63 and 64 of a roller 65 located between said discs. The shaft 62 is journaled for rotation in a bearing 66 in the head 18, while the shaft 61 is a stub shaft which projects through the partition wall 42 and through a cover plate 67 closing the outer face of the housing 34. A manipulating knob 68 is mounted on the protruding outer end of the shaft 61 and is provided with a bayonet slot 69 adapted to engage a pin 70 on said shaft for manually turning the same to wind the supplemental ribbon on the spools respectively.

The sections 63 and 64 of the roller 65 are secured together by screws 72 and have their confronting faces annularly recessed so as to provide confronting peripheral rims 73 and 74 on the sections respectively which rims are formed with diametrically disposed slots 75 and 76 defining rectangular openings 77 and 78 in the periphery of said roller 65. A bar 79 is mounted for reciprocatory movement between said sections with the reduced opposite end portions 80 and 81 of the bar disposed in said openings and adapted to protrude through either one or the other thereof. The slots 75 extend laterally through the walls and peripheral rims of the sections 63 and 64, while the slots 76 are of a depth to extend partway through the rims of the sections whereby the shoulders 83 and 84 formed by the reduced end portions 80 and 81 of said bar are adapted to engage against the inner periphery of the rims laterally of the slots 76 to limit the outward reciprocatory movement of said bar.

The bar 79 is engaged by a leaf spring 85 which extends through a transverse slot 86 therein with the ends of the spring disposed in oppositely disposed V-shaped notches 87 in the inner periphery of the rim 73. The said spring is bowed so as to resiliently maintain the bar 79 with the outer ends thereof protruding through either one or the other of the openings 77 and 78 in the roller 65. When the spring is bowed in one direction the reduced end portion 80 projects through the opening 77 as illustrated in full lines in Fig. 6 of the drawings and when the spring is flexed to the broken line position shown in Fig. 6 of the drawings, the reduced end 81 of the bar protrudes through the opening 78. When in the former position the spring is engaged against a stop pin 88 secured to the section 63 and when in the latter position, the spring abuts against a stop pin 89 carried by said section, the said stop pins and the notches 87 being disposed in alignment. The spring 85 thus operates as an overcenter snap spring which moves the bar 79 from one position to the other when the bar is

initially moved inwardly of the periphery of the roller 65.

The bar 79 is formed with reversely directed cam faces 92 and 93 at the ends thereof which are adapted to be engaged by lugs 94 and 95 formed integrally with the discs 57 and 58 respectively and which project laterally into overlying relation with the rims 73 and 74 of the sections 63 and 64. The lugs 94 and 95 are normally disposed against the bottom of the cam faces 92 and 93 respectively when the same protrude through the openings 71 and 73 in the roller 65 so as to operatively connect one of the spools 40 and 41 with the shaft 62 for rotation to wind the supplemental ribbon thereon with the other spool being free to rotate to permit of the free unwinding of the supplemental ribbon therefrom. When the ribbon is fully wound on one of the spools 40 and 41, rotation thereof and its disc is prevented. The shaft 62 and the roller 65 are free to rotate however, which functions to cam one of the lugs 94 and 95 against one of the cam faces 92 and 93 to thereby force the bar 79 inwardly against the tension of the spring 85 so as to cause the spring to snap into the oppositely bowed position. The bar 79 is then moved to project its opposite end through the roller 65 whereby the full spool is rendered free to rotate and the empty spool is operatively connected with the shaft 62 for rotation to thereby wind the supplemental ribbon thereon.

With the shifting of the carriage from left to right, the shaft 62 is rotated in a counter-clockwise direction as viewed from the front of the machine by means of a spring tensioned ratchet mechanism 98 operatively connected with a flexible tape 99 secured at one end to the frame of the machine adjacent the rear post 100. The ratchet mechanism 98 includes a ratchet wheel 101 secured to the inner end of the shaft 62 protruding into a housing 102 at the rear of the head 18. A spool 103 is rotatably mounted on the shaft 62 at one side of said ratchet wheel and to which spool the other end of the tape 99 is secured and adapted to be wound thereon. A spring pressed pawl 104 pivoted to the forward face of the spool 103 is disposed in engagement with the ratchet wheel 101 for rotating the same with the movement of the spool in a counter-clockwise direction as the tape is unwound therefrom with the return of the carriage from left to right. A spring pressed pawl 105 is pivoted to the inside face of the housing 102 and engages the ratchet wheel 101 to prevent clockwise movement thereof. The spool 103 is rotated to wind the tape 99 thereon by a torsion spring 106 which is disposed in an annular recess 107 in the side face of said spool with the inner end of the spring secured to the hub 108 and the outer end of the spring secured to a pin 109 carried by a cross-bar 110 affixed to the housing 102 with the shaft 62 freely protruding through an opening 111 therein to thereby retain the spool 103 for free turning movement thereon. The tape 99 is trained through an opening 112 in the housing 102 and thence upwardly over an idler roller 113 with the upper end of the tape attached to the periphery of the spool 103. It will be understood that as the carriage is returned from left to right, the spool 103 will be rotated on the shaft 62 to play out the tape 99 therefrom with the pawl 104 engaging the ratchet wheel 101 to rotate the same and the shaft 62 together with the roller 65 with the rotation of said spool. This winds the spring 106

within the spool 103. It follows therefore, that each time the carriage is returned from left to right, the shaft 62 is rotated to drive one of the gears 35 and 36 to rewind the supplemental ribbon on one or the other of the spools 40 and 41 as hereinbefore explained. When the carriage is moved from right to left during the typing operation, the spool 103 is rotated on the shaft 62 by the torsion spring 106 to thereby wind the tape 99 thereon with the pawl 104 freely ratcheting over the ratchet wheel 101.

The frame 19 is retained in operative position by a spring latch 116 pivoted to the outer end 117 thereof and adapted to engage a latch opening 118 in the bottom wall of an upstanding guide channel 119 affixed to the carriage frame. The latch 116 is mounted in a slot 120 on a pivot pin 121 extending through an outwardly projecting portion 122 of the outer end 117 which projecting portion 122 slidably fits the guide channel 119 to firmly retain the rectangular frame 19 against movement when in latched operative position. The frame is released from latched engagement by manually pressing the upper end 124 thereof inwardly against the tension of the spring 125.

The sheaths 20 and 21 are of continuous formation being connected together by a bight portion 126 which extends circumferentially about the outer portion of the pin 56 so as to form a continuous guide for the supplemental ribbon extending from the open end 44 in the sheath 20 throughout said sheath and thence about the pin 56 and throughout the sheath 21 to the open end 45 thereof. The said sheaths are spaced apart in adjacent side by side parallel relation as illustrated in Fig. 12 of the drawings when the frame 19 is in latched operative relation. Sufficient space is provided between the sheaths when in said side by side operative relation to permit of the movement of the paper therebetween with the turning of the platen or roller 15. The sheath 21 is connected to the spring latch 52 for movement to a spread apart relation as illustrated in Fig. 10 of the drawings with the upward swinging movement of the frame 19 from latched operative position. The spreading apart of the sheaths is to permit of the initial insertion of the sheets of paper with reference thereto as hereinbefore described. The spring latch 52 is pivoted in a bearing 127 carried by the carriage frame and is engaged by a spring 128 to normally rotate the latch to dispose the sheath 21 in the spread apart position. The latch is formed with a curved edge 129 which engages against a stop bar 130 affixed to the carriage frame when the frame 19 is swung downwardly towards latched operative position so as to swing the latch bar in its bearing 127 from the angular position shown in Fig. 10 of the drawings to the vertical position shown in Fig. 9. The sheaths are formed of relatively thin sheet material approximately three-thousandths of an inch in thickness and the same are of flattened tubular formation so as to provide longitudinally extending grooves 131 and 132 above and below the slots 26 and 27 in the opposite side walls thereof. The sheaths are adapted to be maintained in taut condition by adjusting the outer end 117 of the frame 19 with reference to the top bar 133 thereof. This is accomplished by turning the set screw 134 which is threadedly engaged in an opening in the outer end 117 and abuts against the end of the top bar 133. The sheath 21 may also be tightened by rotating the adjusting nut 135 which

threadedly engages the pivot pin 53 protruding through the bearing 127.

The head 18 is adapted to be affixed to any standard typewriting machine. For this purpose, the head includes a bracket 136 which is pivoted at its lower end on the pivot pin 29 between the pintles 30 as hereinbefore set forth. The shaft 62 is journaled in a tube 137 secured in a bore 138 in the split upper end 139 of said bracket which is provided with screws 140 for securing the tube in position therein. The ends of said tube are secured in split bosses 141 and 142 formed respectively on the housings 34 and 102 by tightening the screws 143 therein. This spaces the housings 34 and 102 from the bracket 136 and permits of the use of different lengths of tube 137 for accommodating different widths of typewriter carriages.

The ends of the supplemental ribbon 24 are secured to the hubs or spools 40 and 41 respectively between a metallic sleeve 150 and a semi-cylindrical spring 151. The hubs or spools 40 and 41 are formed with oppositely disposed notches 152 and the sleeve 150 and spring 151 are correspondingly bowed to engage in the notches 152. A cap 153 having prongs 154 frictionally engages in the notches 152 in overlying relation with the spring 151 for retaining the same in position.

Instead of the ribbon guides 20 and 21, two ribbon guides 156 and 157 may be provided as illustrated in Figs. 18 and 19 of the drawings which are fashioned from a flat metallic strip bent about the post 56 with one end of the strip affixed to the extension 49 of the housing 34 and the other end of the strip affixed to the spring latch 52. The said guides 156 and 157 are formed with rectangular slots 158 and 159 opening medially therethrough substantially the length of the platen of the carriage and which slots are approximately the same width as the width of the supplemental ribbon 24 for slidably receiving the leads or courses 22 and 23 respectively. The ribbon guide 156 is provided with cleats 160 and 161 secured thereto at the opposite ends of the slots 158 to thereby provide guide openings 162 and 163 through which the lead or course 22 is trained to extend longitudinally of said slot 158. The said lead or course engages through the guide opening 163 and is trained peripherally about the post 56 and longitudinally of the slot 159 through a guide opening 164 at one end thereof and through a guide opening 165 at the opposite end thereof formed by cleats 166 and 167 secured to the outer face of the ribbon guide 157. The lower longitudinal edges of the slots 158 and 159 form ledges 168 and 169 on which the leads or courses 22 and 23 are supported in the slots 158 and 159, the ribbon guides being of a thickness to prevent smudging or smearing contact of the paper against the supplemental ribbon when the paper is moved by turning of the platen relative to the ribbon guides as provided by the ribbon guides 20 and 21. The upper and lower longitudinal edges of the slots 158 and 159 retain the ribbon guides in position therein. The post 56 is secured at its opposite ends in a yoke 171 affixed to the lower terminal of the outer end 117 of the frame 19.

In using the attachment, a plurality of sheets of paper fragmentarily illustrated as C, D, E, F, and G in Fig. 15 of the drawings are trained about the platen or roller of the typewriting machine with the upper ends thereof projecting

above the platen or roller. The frame 19 is released from latched engagement with the spring latch 116 whereby the ribbon guides are spread apart as illustrated in Fig. 10 of the drawings. 5 This permits of the insertion of the sheets D and E on opposite sides of the ribbon guide 21 and the sheets F and G on opposite sides of the ribbon guide 20 with the forward sheet C at the rear of the typewriter ribbon 13. When so arranged, the frame 19 is then moved to latched engagement with the spring latch 116 and the carriage together with the attachment shifted to the right in the usual manner for typing. When the sheets of paper are to be removed 15 from the machine, the frame 19 is released from latched engagement with the spring latch 116 and rotated to its inoperative position where it is retained in upright relation by means of the stop lug 172 carried by the bracket 136 and adapted to engage against the underside of the pintles 30 for limiting the upward swinging movement of the head 18 and frame 19.

When only a single carbon copy is desired, a masking strip 173 of flexible material is removably secured to the forward ribbon guide in any desired manner such as by the pins 174 carried by the cleats 166 and 167 of the ribbon guide 157 which engage through openings in metallic ends 175 to which the masking strip 173 is secured at its ends. When the said masking strip is employed, the original sheet C is disposed at the rear of the typewriter ribbon 13 and a sheet of paper such as the sheet G is arranged at the rear of the rearmost guide 20 as shown in Fig. 30 15 or 156 as shown in Fig. 19.

The foregoing description and mode of operation is illustrative of the particular form of the invention described and various modifications may be made in the embodiments illustrated 40 without departing from the spirit of the invention.

What is claimed is:

1. A multicopy attachment for typewriting machines including a support adapted to be affixed to the reciprocatory carriage of the machine at one end thereof, a pair of horizontally aligned ribbon guides of a length to extend from one side of said carriage to the other and having aligned horizontally disposed openings extending longitudinally thereof substantially the length of the platen of the carriage, a frame to which said guides are affixed at their ends, a guide carried by said frame at one end of said ribbon guides, a pair of ribbon spools rotatably mounted on said frame at the end thereof opposite said second mentioned guide adapted to receive thereon the ends of a supplemental ribbon, said supplemental ribbon being trained through said aligned ribbon guides and around said last mentioned guide to provide two supplemental ribbon courses located at the rear of the typewriter ribbon for receiving on said supplemental ribbon courses through said openings the impression of the type against the typewriter ribbon, said frame being pivoted on said support for swinging movement of the frame from an operative position in which the aligned ribbon guides are disposed in parallel relation with the ribbon of the typewriter machine to an inoperative position in which the aligned ribbon guides are located in upright relation at one end of the carriage, means carried by said frame and the carriage for latching the frame in operative position, and means connecting one end of one of said

aligned ribbon guides with said frame for movement from adjacent relation with the other ribbon guide to a spread apart horizontally aligned relation for facilitating the insertion of paper therebetween when the frame is released from operative position.

2. A multicopy attachment for typewriting machines including a support adapted to be affixed to the reciprocatory carriage of the machine, a frame affixed to said support and a pair of horizontally aligned ribbon guides of a length to extend from one side of the carriage to the other and affixed at their ends to said frame and having aligned horizontally disposed openings extending longitudinally thereof substantially the length of the platen of the carriage, a post affixed to said frame and located at one end of said guides, a pair of ribbon spools rotatably mounted on said frame at the end thereof opposite said post adapted to receive thereon the ends of a supplemental ribbon, said supplemental ribbon extending longitudinally through the openings in said ribbon guides and around said post to provide two supplemental ribbon courses located at the rear of the typewriter ribbon and wholly within said openings for receiving on said supplemental ribbon courses in said openings the impression of the type against the typewriter ribbon, and means rotating either one or the other of said spools with the movement of the carriage from left to right for winding the supplemental ribbon thereon and moving said ribbon in one direction in one of the guides and in the other direction in the other guide.

3. A multicopy attachment for typewriting machines including a support affixed to the reciprocatory carriage of the machine at one end thereof, a rectangular shaped frame including a head at one end thereof, a depending bar at the opposite end, a top bar connecting the upper end of the head and the depending bar and a pair of horizontally aligned ribbon guides affixed at their ends to the lower end of said head and depending bar and having aligned horizontally disposed openings extending longitudinally thereof substantially the length of the platen of the carriage adapted to receive a supplemental ribbon extending longitudinally through the openings in said guides and around one end thereof to provide two supplemental ribbon courses located wholly within said openings for receiving thereon in said openings the impression of the type against the typewriter ribbon, said head being pivoted on said support for swinging movement of the frame from an inoperative upright position at one end of the carriage to an operative position in which the guides extend longitudinally of the carriage and with the openings in the guides arranged at the striking position of the type of the machine, and means carried by said depending bar and the carriage for latching the frame in operative position.

4. A multicopy attachment for typewriting machines including a support affixed to the reciprocatory carriage of the machine at one end thereof, a rectangular shaped frame including a head at one end thereof, a depending bar at the opposite end, a top bar connecting the upper end of the head and the depending bar and a pair of horizontally aligned ribbon guides of a length to extend from one side of said carriage to the other and affixed at their ends to the lower end of said head and depending bar and having aligned horizontally disposed openings extending longitudinally thereof substantially the length of

the platen of the carriage adapted to receive a supplemental ribbon extending longitudinally through the openings in said guides and around one end thereof to provide two supplemental ribbon courses for receiving thereon in said openings the impression of the type against the typewriter ribbon, said head being pivoted on said support for swinging movement of the frame from an inoperative upright position at one end of the carriage to an operative position in which the guides extend longitudinally of the carriage and with the openings in the guides arranged at the striking position of the type of the machine, and means carried by said frame for tensioning the guides to render the same taut.

5. A multicopy attachment for typewriting machines including a support affixed to the reciprocatory carriage of the machine at one end thereof, a rectangular shaped frame including a head at one end thereof, a depending bar at the opposite end, a top bar connecting the upper end of the head and the depending bar and a pair of horizontally aligned metallic ribbon guides of a length to extend from one side of the carriage to the other affixed at their ends to the lower end of said head and depending bar and having aligned horizontally disposed openings extending longitudinally thereof substantially the length of the platen of the carriage, a guide carried by the frame at one end of said metallic ribbon guides, a pair of ribbon spools rotatably mounted on said head opposite said second mentioned guide adapted to receive thereon the ends of the supplemental ribbon, said supplemental ribbon being trained through said metallic ribbon guides and around said last mentioned guide to provide two supplemental ribbon courses located at the rear of the typewriter ribbon for receiving on said supplemental ribbon courses through said openings the impression of the type against the typewriter ribbon, said head being pivoted on said support for swinging movement of the frame from an operative position in which the metallic ribbon guides are disposed in parallel relation with the typewriter ribbon to an inoperative position in which the metallic ribbon guides are located in upright relation at one end of the carriage, means carried by the depending bar and the carriage for latching the frame in operative position, and pivotal latch means on said head connecting one end of one of said ribbon guides with said head for movement from adjacent relation with the other ribbon guide to a spread apart horizontally aligned relation for facilitating the insertion of paper therebetween when the frame is released from operative position.

6. In a typewriting machine, a frame affixed to the reciprocatory carriage thereof, said frame having a pair of horizontally aligned flat bars providing ribbon guides of a length to extend from one end of the carriage to the other and affixed at their ends to said frame, said bars having aligned horizontally disposed openings extending longitudinally thereof substantially the length of the platen of the carriage, said openings being of a height to receive a supplemental ribbon extending longitudinally through the openings in said bars and the bottom edges of the bars defined by the openings being of flat formation for engagement of the lower edge of the supplemental ribbon thereon, and means at the ends of said bars for guiding the supplemental ribbon in and out of said longitudinally extending openings in the bars.

7. In a typewriting machine, a rectangular

shaped frame including a head at one end thereof affixed to the reciprocatory carriage of the machine, a depending bar at the opposite end, a top bar connecting the upper end of the head and depending bar and a pair of horizontally aligned flat bars providing ribbon guides of a length to extend from one end of the carriage to the other and affixed at their ends to the lower end of said head and depending bar, said bars having aligned horizontally disposed openings extending longitudinally thereof substantially the length of the platen of the carriage to receive a supplemental ribbon extending longitudinally of the openings in said guides and around one end thereof to provide two supplemental ribbon courses for receiving thereon in said openings the impression of the type of the machine.

BEULAH LOUISE HENRY.
